CLAIM

The ornamental design for a camera bracket, as shown and described.

DESCRIPTION

FIG. 1 is a perspective view showing my new design;
FIG. 2 is an environmental view showing the camera bracket on the outside of a vehicle door, the broken lines depict the side mirror and the outside of a vehicle door of which the camera bracket is mounted to, and which forms no part of the claimed inventions thereof;
FIG. 3 is the front view thereof;
FIG. 4 is the rear view thereof;
FIG. 5 is the right side view thereof;
FIG. 6 is a top view thereof; and,
FIG. 7 is a bottom view thereof.

The left side view is not depicted and mirrors the right side view in FIG. 5; and

The broken lines in FIG. 2 depict environmental structures of a camera and exterior vehicle door and form no part of the claimed invention.
